[57] **CLAIM**

The ornamental design for a combined stand and housing for a video display unit, as shown and described.

DESCRIPTION

FIG. 1 is a front elevational view of a combined stand and housing for a video display unit showing my new design;

FIG. 2 is a side elevational view thereof, the opposite side being similar except for the extrusions on the base plate;

FIG. 3 is a top plan view thereof;

FIG. 4 is a rear elevational view thereof;

FIG. 5 is a front elevational view of a second embodiment of my new design;

FIG. 6 is a side elevational view thereof, the opposite side being similar except for the extrusions on the base plate;

FIG. 7 is a rear elevational view thereof;

FIG. 8 is a top plan view thereof.

FIG. 1.

FIG. 2.

FIG. 3.

FIG. 4.

FIG. 5

FIG. 6

FIG. 7

FIG. 8
